UNITED STATES PATENT OFFICE.

RICHARD W. TANNER, OF ALBANY, NEW YORK.

PEDAL.

SPECIFICATION forming part of Letters Patent No. 372,776, dated November 8, 1887.

Application filed March 5, 1887. Serial No. 229,891. (No modcl.)

To all whom it may concern:

Be it known that I, RICHARD W. TANNER, a citizen of the United States, residing at Albany, in the county of Albany and State of New York, have invented certain new and useful Improvements in Pedals and Mountings for Pianos and Organs; and I do hereby declare that the following is a full, clear, and exact description of the invention, which will enable others skilled in the art to which it appertains to make and use the same.

My invention relates to piano and organ pedals and means for mounting them, and is designed to provide a bearing for the pedal-pins that will obviate the defects common to metallic bearings; further, to provide suitable means for adjusting and renewing said bearings; also, to provide means for adjusting the pedal-feet relatively to each other, and, further, to protect the opening in the piano or organ frame traversed by the pedal from mice, dirt, and all foreign matter.

In the accompanying drawings, Figure 1 represents a top view of pedal bracket or hinge-plate; Fig. 2, a bottom view of same; Fig. 3, a top view of pedals attached to hinge-plate; Fig. 4, a bottom view of pedal-bracket and pedals with a downward-projecting plate. Fig. 5 is a perspective view of plug used with pedal-bracket. Fig. 6 is a longitudinal cross-section of part of pedal-shank, showing the underhanging plate c. Fig. 7 is a cross-section of vertical projection A through line 4.

Similar letters refer to similar parts throughout.

The hinge-brackets are composed of base-plates A and B, having on the outer ends lateral projections, through which openings e are made for screws to fasten it to the piano or organ frame. Their inner ends are also provided with lateral projections, one of which having a longitudinal slot, while the corresponding end of the adjoining plate has a lateral projection having its edges provided with downward-projecting flanges b', substantially parallel with each other, adapted to engage with the slotted end, and is provided with a hole, b, through which a screw may be passed to fasten the plate to the organ or piano. The screw may be moved along the slot a. The overlapping projection is drawn down and pressed upon the slotted end by the screw, thereby holding

the inner ends of the plates firmly in position. If desired, the slotted and overlapping ends may be dispensed with and the inner ends of hinge-plate made to correspond with the outer ends or ears of same; or the groove of the lower plate may be omitted and an ear similar to those on the outer ends of hinge-plate may be attached to the overlapping projection, the parallel flanges b' projecting downward on each side of the ear underneath. The hinge-plate is also provided with vertical projections A', which are hollowed out, the opening d extending from the bottom surface of the plate to a height at which it is desired to hinge the pedal. The upper surface of this recess d is preferably made rounding to provide a bearing for the pedal-pins. Within this opening, at the upper end, on the rounded surface, may be placed a covering of leather or other material having similar capabilities.

The pedal C, having a pin extending transversely through its shank, is placed in position between the upright projections A', the pedal-pin within the opening d resting on the leather surface. The leather may be omitted and the pin made to bear on the metal surface within the groove. I prefer, however, to use a non-metallic bearing. When the pin is in position, a plug of wood, D, or other suitable material corresponding in shape to the inner surface of the opening d, is pressed into the opening until the wood bears upon the pedal-pin. The plug should be slightly larger than the opening, in order that it may be held firmly in position when forced into the opening. Should the bearing become loose from wear or other cause, the plug D can be pressed further into the opening until it bears upon the pedal-pin.

The shape of the upright projections may be varied somewhat without departing from my invention, the essential feature of the projection being the recess opening into the space occupied by the pedal between the vertical projections. The slot or recess may be made horizontal, if desired, instead of vertical.

The outer sides of the uprights are shown beveled, and are made so for convenience in molding. They may be made parallel instead, and the recess made to open on the outer side of the projection as well as on the inner.

Attached to the under surface of the pedal C is a downward-projecting plate, e, substantially

equal in width to that part of the pedal-shank where it is attached. This projection is attached to the pedal at a point on the shank near the outer surface of the organ or piano case when in its place in the piano, and should be long enough to cover the slot traversed by the pedal even when the pedal is at rest, thereby excluding mice, dirt, and all other extraneous matter from the frame.

10. What I claim as new, and desire to secure by Letters Patent, is—

1. A piano or organ pedal pivotally connected to a hinge-bracket having a detachable bearing for the pedal-pin, substantially as shown and described.

2. A piano or organ pedal pivotally connected to a hinge-bracket provided with an opening adapted to hold a detachable bearing for the pedal-pin, substantially as shown and described.

3. Piano or organ pedals pivotally connected to hinge-brackets having base plates provided with ears or lateral projections, the inner ears arranged one above the other, and means for adjustably securing said ears to the piano or

organ frame, substantially as shown and described.

4. Piano or organ pedals pivotally attached to pedal-brackets having their base-plates provided with lateral projections, the inner projections arranged one above the other, the under one provided with a longitudinal slot, substantially as shown and described.

5. A piano or organ pedal pivotally connected to a hinge-bracket having vertical projections, each provided with a slot, and means contained therein for adjusting the bearing to the pedal-pin, substantially as shown and described.

6. A piano or organ pedal having its entire 40 under surface in substantially the same horizontal plane, and provided on its under surface with a downward-projecting plate extending transversely across the shank of the pedal, substantially as shown and described.

RICHARD W. TANNER.
